DESIGN.

J. W. MAYER.

RING OR SIMILAR ARTICLE.

APPLICATION FILED SEPT. 15, 1921.

59,665.

Patented Nov. 15, 1921.

Inventor

Joshua W. Mayer.

By his Attorney
Leavenworth & Hocky

UNITED STATES PATENT OFFICE.

JOSHUA W. MAYER, OF NEW YORK, N. Y.

DESIGN FOR A RING OR SIMILAR ARTICLE.

59,665.

Specification for Design.

Patented Nov. 15, 1921.

Application filed September 15, 1921. Serial No. 500,981. Term of patent 7 years.

To all whom it may concern:

Be it known that I, JOSHUA W. MAYER, a citizen of the United States of America, residing at New York city, county and State of New York, have invented a new, original, and ornamental Design for a Ring or Similar Article, of which the following is a specification, reference being had to the accompanying drawing, forming part hereof, in which—embodying my new design, and Fig. 2 is an edge view thereof.

I claim:

The ornamental design for a ring or similar article, as shown.

Signed at New York city, N. Y., this 12 day of Sept., 1921.

JOSHUA W. MAYER.

Witnesses:

EDW. SUMNICK,
JOHN GRAETZER.
